MERCHANTISING DEVICE

James C. Calhoun, New Haven, Wilbur L. Davidson, Westport, Conn., and Karl J. Hansen, Forest Hills, N. Y., assignors to Western Cartridge Company, East Alton, Ill., a corporation of Delaware

Application April 25, 1941, Serial No. 390,236

12 Claims. (Cl. 211—13)

The invention relates to merchandising devices and, more particularly, to counter stands for displaying flashlights, flashlight accessories and the like.

According to a preferred form of the invention the stand comprises a body member of cardboard or the like bent to form upper and lower front and side walls and upper and intermediate top walls, these walls forming steps or tiers having recesses for displaying flashlights and the like. Secured to the rear edges of the upper side walls is a back wall or panel containing advertising. Secured to the lower part of the lower walls is a tray member formed from cardboard bent to form an inclining bottom wall and front and side walls suitably connected to the body member. For holding the stand in set-up position a reinforcing member is provided having front and side panels with corresponding bottom panels connected to the corresponding top, side and front walls of the body member. These parts are so hingedly connected as to permit the stand to be collapsed for shipment. They also hold the stand in set-up condition by bending suitable wings out of the reinforcing member to engage under said intermediate top walls.

The invention also consists in certain new and original features of construction and combination of parts hereinafter set forth and claimed.

Although the novel features which are believed to be characteristic of this invention will be particularly pointed out in the claims appended here-to, the invention itself, as to its objects and advantages, and the manner in which it may be carried out, may be better understood by referring to the following description taken in connection with the accompanying drawings forming a part thereof, in which—

Fig. 1 is a perspective view of the new merchandising stand and showing how a flashlight may be supported and displayed in the stand;

Fig. 2 is a plan view and partial section as viewed along the line 2—2 of Fig. 1;

Fig. 3 is a vertical section on the line 3—3 of Fig. 2;

Fig. 4 is a fragmentary plan section taken on line 4—4 of Fig. 3;

Fig. 5 is a rear view of the main portion of the stand in a partially collapsed position, the two lateral wings or sides having been rotated towards the observer;

Fig. 6 is a plan section taken on line 6—6 of Fig. 5;

Fig. 7 is a front view of the stand in fully

collapsed position ready for packing for shipment or storage;

Fig. 8 is a detail showing a special form of score for making a smooth unbroken edge;

5 Figs. 9 to 12, inclusive, show the blanks from which the stand is made.

In the following description and in the claims, various details will be identified by specific names for convenience, but they are intended to be as generic in their application as the art will permit.

Like reference characters denote like parts in the several figures of the drawings.

Referring now to the drawings and more particularly to Figs. 9—12, inclusive, the several blanks of cardboard or other suitable material are denoted by reference letters A to D. Cuts are shown by solid lines and scores by dot-and-dash lines. Excepting blank D, all the blanks may be made up of a moderately heavy paperboard or cardboard having a surface layer of paper adapted for printing or coloring in a manner to form an attractive advertising display. The blank D, not being visible when the stand is in use, may be made of cardboard which is unsurfaced but sufficiently strong for its purpose of reinforcing and supporting the stand when the latter is set up in the display position.

Referring now to the other figures and more particularly Fig. 1, the blank A forms the main body of the display stand comprising a lower front wall 10, lower side walls 11, 12, upper front wall 13, upper side walls 14, 15, intermediate front and side shelves 16, 17, 18 and a top shelf 19 composed of three portions 20, 21 and 22.

The blank B forms the back wall 23 of the stand, which at its upper portion extends a considerable distance above the top shelf 19 so as to provide a surface upon which printed advertising may be placed.

40 The blank C, when properly folded and attached to the front wall 10 and side walls 11, 12 of blank A forms a tray 24 having a front wall 25, side walls 26, 27 and 28, 29, which may be angularly disposed in relation to each other and to the front wall 25, and a bottom wall comprised of three portions 30, 31, 32.

The blank D forms a reinforcing member having a central panel 35 (Fig. 2) and lateral panels 36, 37, which, when attached to the back of the wall portions of blank A in a manner to be described hereinafter, provides a means whereby the front and side walls and the shelves of the blank A are forced to assume their proper relative positions as the stand is unfolded from its col-

lapsed position to its display position. Each of the panels 35, 36, 37 has a positionable wing 38 formed therein which serves to maintain the stand in display position when swung inwardly beneath the intermediate shelves 16, 17, 18.

The shelves 16, 17, 18 and 19 are provided with recesses, as indicated especially in Figs. 1 and 3, to hold a series of flashlights, one of which is indicated by 40. These recesses may be of different sizes and shapes to hold different sizes and types of flashlights.

The blanks A, C and D are assembled at the factory where the stand is made preferably by glue, metal fasteners or both. The assembled stand is collapsed and shipped flat along with the blank B which is folded once to reduce its shipping size. Fig. 7 indicates the stand body in collapsed condition as received by the merchant who, to prepare the stand for display purposes, merely opens the stand, bends certain parts at the scores, connects the interlocking tongues and slots and attaches the back blank B by other tongues and slots to complete the stand for receiving the flashlights, as will hereinafter more fully appear.

The method of assembling the stand at the factory is as follows:

The main blank A is provided with flanges 41, 42 along the inner edges of the walls 14, 15 and glue is applied to their outer surfaces. The blank is then bent along its various scores to approximate its shape in the display position, after which the glued flanges 41, 42 are secured along the sides of the back of wall 13 in such a manner that the score lines 43, 44 coincide with the edges of wall 13 and the bottoms of the glued flanges 41, 42 fall along the score line 45 of wall 13. Blank A is now ready for the attachment on its back face of the reinforcing blank D.

The blank D (Fig. 12) is provided with flanges 46, 47 and 48 at the bottoms of panels 35, 36 and 37, and panels 36 and 37 are further provided with tabs 49 and 50 midway of their outer edges, the tabs 49, 50 also having flanges 51, 52. The upper ends of panels 35, 36, 37 are slightly reduced in width as indicated at 53, 54, 55. Glue is applied on the face of the flanges 46, 47, 48, 51 and 52 and on the opposite face of reduced portions 53, 54 and 55. The central flange 46 is then bent back upon itself along the score line 56 and attached to the back of wall 10 of blank A along the central portion of the bottom edge thereof (Fig. 3) in such a manner that the score line 56 coincides with the bottom edge of wall 10. The glued portion 53 of blank D is then secured to the central lower portion of wall 13 of blank A in such a manner that the cut line 57 forming the top edge of the wing or flap 38 falls just below the score line 45 of blank A.

Similarly, the glued flanges 47 and 48 of blank D are bent back upon themselves along scores 58, 59 and attached respectively to the bottom edge of walls 11, 12 of blank A (Fig. 5), care being taken to bring the outer ends of flanges 47, 48 substantially along the outer edge of the respective walls of blank A to which it is attached and to bring the score lines 58, 59 along the bottom edge of walls 11 and 12. The glued portions 54, 55 of blank D are then attached respectively to the back of walls 14, 15 of blank A so that their outer edges lie substantially along the outer edge of the respective walls 14, 15 and the upper cut line 57 of each of the outer wings 38 falls just beneath the score lines 60, 61 of blank A.

Further reinforcement is provided between the

blanks A and D by the tabs 49 and 50 on blank D wherein the glued flanges 51, 52 of the tabs are bent back upon themselves along the score lines and attached respectively to the proper place on the back face of the walls 11, 12 of blank A, it being noted that this portion of attachment is automatically attained due to the particular placement of scores and the previous attachment of the rest of the blank D to blank A.

It is to be further noted that it is preferable, although not necessary, to form the various score lines on the blank D in such a manner as to provide a sharp corner when the blank is bent and this may be attained by methods well known in the art such as forming the score by partially cutting the cardboard on that side away from which the part is to be bent.

The tray 24, formed from the blank C, is assembled on the main body of the stand by attaching the flange 70 of blank C to the bottom of the outer surface of the wall 10 of blank A as by metal clips 71, or by glue if desired. The portions of the blank C which form the side walls of the tray 24 may then be folded towards each other along score lines 72, 73, and 74, 75 so as to lie against the central section 25, 25', 30, thereby reducing its width when in shipping condition as shown in Fig. 7. The portions 25, 27, 29 of blank C are particularly adapted to receive advertising printed matter.

It will thus be seen that, due to the particular proportions of the blanks A and D and their attachment to each other in the manner above described a mutual displacement of their various surfaces takes place as the stand in either opened from its collapsed position or closed from its display or set-up position. This may be best understood from a study of Fig. 5 which shows a back view of the stand partially closed, the two sides of the stand being indicated as substantially at right angles to the central section and on their way towards each other (as indicated in Fig. 6) so that, when fully collapsed, one side will lie flat against the back of the central section and the other side flat against the side just mentioned.

As will be observed from Figs. 5 and 6, when the two sides of the stand are swung rearwardly and towards each other, the walls 11, 12 of blank A rotate about their respective axes c and d formed by scores 80, 81 while the panels 36, 37 of blank D rotate respectively about axes a and b formed by scores 82, 83. However, due to the interconnection between blank A and blank D formed by the sections 85, 86, 87 on the bottom of panels 35, 36, 37, the central section of the stand, comprised by the wall 13, shelves 16 and 20, and the panel 35, moves upwardly and towards the front wall 10 in a movement similar to that of the bars of a parallel ruler or pantograph, the shelf 16 and section 85 serving in the same capacity as the pivoted links of the parallel ruler.

This movement of the central section of the stand is forced upon it by a similar movement imparted to the side sections wherein the rotation of side walls 11 and 12 about their axes c and d forces the panels 36 and 37 upwardly with respect to walls 11, 12 as they in turn rotate about their axes a and b. The latter rotation is given to the panels 36 and 37 through their connection to side walls 11 and 12 by the tabs 49 and 50 and sections 86 and 87 but the axes a and b, being prevented from traveling in the arcuate paths of side walls 11 and 12 because they are common to the central panel 35, move upwardly

and towards the front wall 10, carrying with them the panel 35 which describes the parallel ruler movement previously mentioned.

Thus, it will be seen that, as the two side sections of the stand are brought together, one a trifle ahead of the other, the stand is collapsed from its display position to a completely flat condition occupying a minimum of space and hence adapted for economical shipping and storage.

To set up the stand, the merchant opens up the collapsed form by swinging the two side sections of the stand outwardly, until the shelves 16, 17, 18 are in a substantially horizontal position and then by pushing inwardly each of the three wings 38 formed in panels 35, 36, 37 until their top edges are fully beneath the shelves 16, 17 and 18 and their bottom edges overlie the portions 85, 86, 87 of blank D. The main body of the stand is then held in expanded or display position.

The tray 24 may then be set up by first unfolding the blank C from the shipping position (shown in Fig. 7), then bending along the score lines 90, 91, 92, so as to form a vertical aligned wall of areas 25, 25', 26, 26', 27, 27', 28, 28', 29, 29'. Areas 25 to 29 are then bent outwardly and downwardly to form double walls the ends of which are then bent towards the side walls 11 and 12 of the main stand wherein slots 93 and 94 are formed to receive tongues 95 and 96 carried on the ends of sections 26 and 28 of blank C. The bottom walls 31 and 32 of the tray are held in position by their tongues 99 and 100 which fit into slots 101 and 102 cut into the side walls 11 and 12 and so fashioned as to substantially lock the tongues 99 and 100 in their pushed in position.

The back wall of the stand, formed by blank B, is attached to the stand next to further complete the set-up. As shown, the blank B is symmetrical about the score 105 and may be attached to the stand with either end uppermost. The purpose served by this feature is the availability of two areas for printed advertising either of which may be selected for display, as for instance, one directed to winter use of flashlights and the other to summer use. For attaching the blank B to the stand there is provided a pair of tongues 106, 107 on the side walls 14, 15 of the stand which fit into slots 108, 109 formed in blank B and lock themselves therein due to the form of the slots and tongues.

The top shelf 19 is next formed by bending the side portions 21 and 22 of the blank A downwardly along the provided score lines and slipping the tongues 110, 111 into slots 112, 113 of blank B. The central portion 20 of the top of the stand is likewise bent downwardly and its tongue 114 slipped into slot 115 of blank B wherein it is automatically locked.

The blank B is provided with relatively narrow flanges 116 along its vertical edges which, when bent at a slight angle to the face of the blank, serve both as stiffening means and as an ornamentation. The several shelves 16, 17, 18 and 19 have a series of recesses of different sizes to hold different size flashlights, all of which are of similar construction, so it is only necessary to describe one recess in detail.

Referring to Figs. 3 and 4, these holders or recesses are formed by cutting a strap from the shelf portion and wall portion of the stand, which strap has an inclined portion 120 and a top portion 121. This strap is connected at its top to shelf 20 and at its bottom to front wall 13. The

cutting of this strap forms a shelf notch 122 and a wall notch 123. Shelf notch 122 has curved sides to fit the flashlight 40 and enlarged corner portions 124. The recess is so shaped that to place the flashlight in position for display, it must be inserted from above through the shelf notch 122 with the switch guard 125 of the flashlight in line with one of the corner notches 124. After the flashlight is fully seated with its bottom projecting out of the wall notch 123, it is rotated about its own axis to bring the switch guard 125 out of register with corner notch 124. A pilfer-proof construction is thus provided wherein it is impossible to remove the flashlight without rotating it to align the switch guard 125 with one of the notches 124. The straps 120, 121 serve to help guide the flashlight to seat properly when it is inserted in the holder and also to improve the appearance of the stand when one or more flashlights are missing from the display.

Additional recesses of other shapes may be provided in the shelves for displaying flashlights of a type different from that illustrated in Fig. 1. Thus, provision has been made in the top shelf 19 and front wall 13 for displaying a pair of small flashlights (not shown) having the general size and shape of fountain pens. To support such a flashlight the top shelf 20 is provided with an oval hole 130 and the front wall 13 has a similar hole 131 closely adjacent thereto, both holes being of such size as to snugly support the cylindrical walls of the flashlight to be displayed.

The tray 24 is primarily designed for the display of flashlight batteries and boxes of light bulbs although of course other articles may be displayed therein. The inclined bottom walls 30, 31, 32 not only strengthen the structure but tip the merchandise within the tray forward to better catch the eye of the shopper.

It will be understood that, in general, the scores provided for folding or bending the various parts of the blanks may be made in any common way now known in the art. However, to preserve pleasing appearances and to avoid ragged and broken corners the type of score shown in Fig. 8 is desirable at observable corners. In this figure the paper board is indicated by 134 and the paper layer by 135. The special double score 136 makes a nice smooth outer corner, this corner being desirable for exposed corners such as at scores 80, 81 and others of a similar nature.

Thus, a merchandising stand is provided which is relatively inexpensive to manufacture and yet which is rigid and strong in use. The stand is made mostly from heavy cardboard or paper-board, preferably having a surface layer adapted to receive color printing. The reinforcing blank D, of course, needs no surface layer since no printing is carried thereon. Substantially the entire device may be assembled in the factory and collapsed for shipping flat. Setting the stand up for display purposes is a simple matter for the merchant, as well as collapsing it for storage.

The general design of the stand wherein the side walls are at an oblique angle to the front walls and in stepped relation thereto permits a view of the displayed wares from many points, while the flashlights themselves, as supported in their holders, are presented to view at an angle to the vertical so that their tubular portions are more nearly at right angles to the line of sight of a prospective buyer and hence more apt to attract his attention and inspire his admiration.

The stand may be made in any desired size and is particularly adapted for counter display wherein a minimum area of a counter is occupied for displaying attractively a relatively large number of flashlights and related supplies.

The pantograph relationship of the reinforcing member D and main body member A permits ready collapsing of the assembled stand for storage or shipment and ready setting up for use. It also strengthens and reinforces the construction holding the parts, particularly the lower walls, in proper relationship. The back member B holds the upper side and top walls of the body member in position and also serves as an advertising sign or placard calling attention to the display.

While certain novel features of the invention have been disclosed and are pointed out in the annexed claims, it will be understood that various omissions, substitutions and changes may be made by those skilled in the art without departing from the spirit of the invention.

What is claimed is:

1. A display stand for articles of merchandise comprising a main body portion having upper and lower front and side walls with intermediate top walls therebetween, a back wall member having connection with the rear edge of said upper side walls, said upper walls having tapered flaps bent at an angle thereto and having connection with said back wall member and forming upper top walls, said top and front and side walls having notches therein to receive said articles, a tray member having front and side walls and a bottom wall, said bottom wall and said tray side walls having connection with said body side walls.

2. A collapsible display stand for flashlights and the like comprising a main body portion having upper and lower front and side walls with intermediate top walls therebetween, a back wall member having detachable connection with the rear edge of said upper side walls, said upper walls having tapered flaps bent at an angle thereto and having detachable connection with said back wall member and forming upper top walls, said top and front and side walls having notches therein to receive flashlights, a tray member having front and side walls and an inclined bottom wall, said bottom wall and said tray side walls having detachable connection with said body side walls.

3. A display stand for flashlights and the like comprising a main body portion having upper and lower front and side walls with intermediate top walls therebetween, a back wall member having tongue and slot connection with the rear edge of said upper side walls, said upper walls having tapered flaps bent at an angle thereto and having tongue and slot connection with said back wall member and forming upper top walls, said top and front and side walls having notches therein to receive flashlights, a tray member having front and side walls and an inclined bottom wall, said bottom wall and said tray side walls having tongue and slot connection with said body side walls.

4. A stand comprising first inner and outer wall members having upper and lower wall members hingedly connected thereto in pantograph relationship, and second inner and outer wall members having second upper and lower wall members hingedly connected thereto in pantograph relationship, said inner wall members being hingedly connected to each other and said

outer wall members being hingedly connected to each other whereby, when said outer wall members are moved relatively to each other, said inner wall members move with respect to their upper and lower wall members, at least one of said inner wall members having wings hingedly connected thereto adapted to engage under the corresponding upper wall member to hold the stand in set-up condition.

5. A stand comprising a body member having a front wall and side walls extending therefrom, a tray member made from a sheet blank having a flange secured to said front wall, said flange having a central bottom wall attached thereto, a front wall attached to said bottom wall, first side walls attached to said front wall, second side walls secured to said first side walls, bottom wall flaps connected to the said first side walls, said bottom flaps and said second side walls having tongue and slot connection with said body side walls.

6. A merchandise display stand comprising a body member having a front wall and right and left diverging side walls extending obliquely therefrom, a tray member made from a sheet blank having a flange secured to said front wall, said flange having a central bottom wall attached thereto, an inner front wall panel attached to said bottom wall, an outer front wall panel attached to said inner front wall panel, first inner and outer side wall panels attached to said front wall panels, second inner and outer side wall panels secured to said first side wall panels, bottom wall flaps connected to the said first inner side wall panels, said inner and outer panels being folded to form double walls, said bottom flaps and said second side wall panels having tongue and slot connection with said body side walls.

7. A stand comprising a display portion made up of a one-piece blank having upper and lower front and side walls with intermediate top walls therebetween, a reinforcing member made up of a separate one-piece blank having front and side panels having hingedly connected thereto corresponding bottom panels, said reinforcing member being disposed behind said display portion, said front and side panels being substantially coextensively secured respectively to said upper front and side walls, said bottom panels being hingedly connected to the lower margins of corresponding lower front and side walls whereby said front wall, front panel and corresponding top wall and bottom panel are in pantograph relationship, and said side walls and side panels and corresponding top walls and bottom panels are respectively in pantograph relationship, and means to hold said stand in set-up position.

8. A display stand for flashlights and the like comprising a main body portion made up of a blank having upper and lower front and side walls with intermediate top walls therebetween, a reinforcing member made up of a blank having front and side panels having hingedly connected thereto corresponding bottom panels, said front and side panels being coextensively secured respectively to said upper front and side walls, said bottom panels being hingedly connected to the lower margins of corresponding lower front and side walls, strut members hingedly connected to said side panels and hingedly connected to said lower side walls, whereby said front wall, front panel and corresponding top wall and bottom panel are in pantograph relationship, and said side walls and side panels and corresponding top

walls, bottom panels and said struts are respectively in pantograph relationship, and wings hingedly connected to said front and side panels adapted to engage under said top walls to hold said stand in set-up position.

9. In a display stand, a collapsible main body member and a separate back wall member to be attached thereto, said main body member comprising a one-piece display portion and having a separate one-piece reinforcing member, said display portion having upper and lower front and side walls with intermediate top walls therebetween, said upper walls having flaps bent at an angle thereto and adapted to have connection with said back wall member and forming upper top walls, said separate reinforcing member having front and side panels corresponding to the lower front and side walls, and means permanently connecting said front and side panels to said lower front and side walls whereby said body member and reenforcing member may be collapsed before assembly with said back wall member.

10. In a display stand, a collapsible main body member and a separate back wall member to be attached thereto, said main body member comprising a display portion and having a reinforcing member, said display portion having upper and lower front and side walls with intermediate top walls therebetween, said upper walls having flaps bent at an angle thereto and adapted to have attachable connection with said back wall member and forming upper top walls, said reinforcing member having front and side panels corresponding to the lower front and side walls, and means connecting said front and side panels to said lower front and side walls whereby said body member and said reenforcing member may be collapsed before assembly with said back wall member.

11. A stand, comprising a display member made from a single blank and having upper and lower

front and side walls with intermediate top walls therebetween, a separate reinforcing member made from a single blank and having front and side panels corresponding to said lower front and side walls, said upper front wall being hingedly connected to said upper side walls, said lower front wall being hingedly connected to said lower side walls, said front panel being hingedly connected to said side panels, said panels being attached to and substantially co-extensive with said upper front and side walls, said reinforcing member having bottom walls connected thereto and secured to said lower front and side walls, said lower front and side walls having parallelogram relationships with their respective front and side panels and said top and bottom walls, the stiffness of said hinged connections causing said stand to tend to assume a collapsed condition, and means for holding said stand in set-up position against the force exerted by said stiffness.

12. A stand, comprising a display portion having upper and lower front and side walls with intermediate top walls therebetween, a reinforcing member having front and side panels corresponding to said lower front and side walls, said upper front wall being hingedly connected to said upper side walls, said lower front wall being hingedly connected to said lower side walls, said front panel being hingedly connected to said side panels, said panels being attached to and substantially co-extensive with said upper front and side walls, bottom walls connected to said panels and to said lower front and side walls, said lower front and side walls and said front and side panels and said top and bottom walls having parallelogram relationship, said stand being readily collapsible into flat condition, and means for holding said stand in set-up condition.
